UNITED STATES PATENT OFFICE.

GEORGE E. MCCOY AND ERNEST HAWKER, OF MONCTON, NEW BRUNSWICK, CANADA.

JOURNAL BOX.

Application filed January 27, 1927. Serial No. 164,113.

The invention is especially applicable to journal boxes for the axles of locomotives and other railway vehicles, its object being to provide improved means for applying lubricant thereto; and it consists in a structure such as is hereinafter described and as illustrated in the accompanying drawings, in which

Fig. 1 is a transverse section of the vehicle 10 axle and end elevation of the journal box enclosing the same;

Fig. 2 is a detailed sectional view on the line 2—2 of Fig. 1; and

Fig. 3 is a view in perspective of a tray 15 for supporting the lubricant container.

While the invention is applicable to the journal boxes of cars, it is shown in connection with a box of the type commonly used on locomotives. In locomotive practice it is 20 common to locate the journal bearing inside of the wheel, one of its ends being located adjacent to, or actually in contact with, the wheel hub.

Such a box, designated in the accompanying drawings by the numeral 10, arches over the axle 11 and is open at the bottom. The journal bearing or "brass" is represented at 12, and may be of any preferred construction. The lubricant is ordinarily applied by 25 the use of oil-saturated waste, commonly called dope, which is carried in some form of container so disposed within the box that the saturated material is in contact with the lower side of the axle 11, to the end that the 30 bearing surface of the journal may be constantly coated with an oil film.

Difficulty has been found in providing a suitable lubricant container and properly mounting the same within the box so that it 40 will be securely held in proper position for the continuous application of the lubricant to the journal, and the loss of oil prevented should an excess be carried upwardly by the journal.

In the present invention the saturated dope, shown at 13, is placed within a container 14, open at the top and having its end walls, as 15, cut away to concave contour, as 45 represented at 16. The width of the box is such that it fits loosely between the side walls of the box 10, the lower portion being of reduced width, as shown at 17, in order that it may be seated loosely within a supporting tray 18.

The tray 18 takes the form of an oblong 55 rectangular box, preferably open at one end as shown in Fig. 3, the upper margin of its side walls being outwardly flanged, as shown at 19, to rest upon instanding upwardly facing shoulders 20 on the side walls of the 60 journal box. The flanges 19 are prolonged beyond the open end of the tray, such extension being downwardly turned, as shown at 21, to hook over the ends of the shoulders 20, which are adjacent to the wheel hub. 65

A helical spring 22, resting upon the bottom of the tray, forms a seat for the container 14, and is of sufficient length to urge it upwardly and insure contact of the contained dope with the journal 11. 70

Stop and deflector plates 23 are applied to the inner faces of the side walls of the journal box and longitudinally thereof, the upper margins of these plates being welded or riveted to the box. Below the attached portion the plates are offset inwardly, as shown at 24, forming stop shoulders for engagement by the upper margins of the side walls of the container and being so positioned as to prevent the actual engagement of the end walls 15 with the journal. The lower in-standing shoulders of the plates 23 extend into the chamber of the container, and consequently deflect into the latter any lubricant which may drip from the bearing 12. 85

The container 14 being suitably filled with the saturated dope and seated within the tray 18, the two parts are inserted through the open inner end of the box 10, the hook 21 being engaged over the shoulders 20, 90 which are adjacent to the hub of the wheels 25,—care being taken that the end walls 15 of the container receive between them the plates 23. The contents of the container 14 should extend somewhat above the cut-away 95 portions 16 of the container, and the spring 22 insures its contact with the journal 11.

As the fibrous contents of the container settles or becomes somewhat impacted, the container is urged upwardly by the spring 100 22 until its side walls engage the shoulders 24 of the plates 23. The container 14 is refilled from time to time as may be necessary to insure actual engagement of its contents with the journal.

While the invention has been shown and described in a form suitable for use in connection with a common type of engine jour-

nal box, it may be applied to other forms of boxes by suitable changes in shape and dimensions of the parts as may be necessary.

We claim as our invention—

6. 1. A journal box for the axles of railway vehicles having upwardly facing shoulders on the inner sides of its side walls, a tray having lateral shoulders for resting upon the named box shoulders, a container for oil-carrying material carried by the tray, spring means urging the container upwardly, and stops for preventing the contact of the walls of the container with a journal inclosed within the box.
10. 2. A journal box for the axles of railway vehicles having upwardly facing shoulders on the inner sides of its side walls, a tray having lateral shoulders for resting upon the named box shoulders and lugs for engaging the ends of the last-named shoulders, a

25
container for oil-carrying material carried by the tray, spring means urging the container upwardly, and stops for preventing the contact of the walls of the container with a journal inclosed within the box.

3. A journal box for the axles of railway vehicles having upwardly facing shoulders on the inner sides of its side walls, a tray having lateral shoulders for resting upon the named box shoulders, a container 30 for oil-carrying material carried by the tray, spring means urging the container upwardly, and stop and deflector plates secured to the inner faces of the side walls of the journal box and projecting into the container. 35

In testimony whereof we affix our signatures.

GEORGE E. McCOY.
ERNEST HAWKER.
